[57] CLAIM

The ornamental design for faucet handle, as shown and described.

DESCRIPTION

FIG. 1 is a perspective view of our new design of a faucet handle;

FIG. 2 is a top plan view of our new design of the faucet handle;

FIG. 3 is a bottom plan view of our new design of the faucet handle;

FIG. 4 is a front elevational view of our new design of the faucet handle, a rear elevational view thereof being a mirror image of the front elevational view;

FIG. 5 is a right side elevational view of our new design of the faucet handle, a left side elevational view thereof being a mirror image of the right side elevational view.
